UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

REVERSIBLE-FEED CHAIN-STITCH SEWING MACHINE.

Application filed September 8, 1922. Serial No. 586,897.

The invention relates to new and useful improvements in chain stitch sewing machines, and more particularly a machine of the above type wherein a thread carrying 5 looper cooperates with a needle beneath the work support.

An object of the invention is to provide a machine of the above type with a stitching mechanism and devices cooperating therewith whereby a lock chain stitch may be formed, regardless of the direction of the feed of the machine.

A further object of the invention is to provide a machine of the above type wherein 15 a loop positioning finger engages the looper thread between the eye of the looper and the fabric for holding the thread triangle open for the entrance of the needle when the feed is reversed.

20 These and other objects will in part be obvious and will in part be hereinafter more fully disclosed.

In the drawings which show by way of illustration one embodiment of the invention—

Figure 1 is a view partly in section and partly in front elevation of a portion of a sewing machine embodying my improvements;

30 Fig. 2 is a view partly in section and partly in end elevation of a portion of said machine;

Fig. 3 is a view of a portion of the parts shown in Fig. 2, but with the feed reversed;

35 Fig. 4 is a view partly in section and partly in plan of the parts of the forward end of the machine beneath the work support;

Fig. 5 is a sectional view on the line 5—5 40 of Fig. 4;

Fig. 6 is a sectional view on the line 6—6 of Fig. 4;

Fig. 7 is a sectional view on the line 7—7 45 of Fig. 6;

Fig. 8 is a perspective view of the means for supporting and operating the loop positioning finger;

Fig. 9 is a view more or less diagrammatic and partly in section, showing the 50 needle, fabric, work support, looper and positioning finger;

Fig. 10 is a diagrammatic view in plan showing the needle, looper and positioning finger with the feed in a normal direction;

Fig. 11 is a similar view but showing the 55 feed reversed, and

Fig. 12 is a view similar to Fig. 11, but showing the positioning finger as about to engage the looper thread.

The invention is directed broadly to a 60 machine which includes a thread carrying needle and a thread carrying looper which cooperates with said needle in forming lock chain stitches. The stitch forming mech-

anism is of the usual construction. Co- 65 operating with the stitch forming mech-

anism is a loop positioning finger which en- 70 gages the looper thread between the eye of the looper and the fabric where the looper thread concatenates with the loops of the

previous stitch. The machine includes a re- 75 versible feed so that the fabric may be fed away from the operator or reversed and fed in a direction toward the operator. This

loop positioning finger engages the looper 76 thread and holds the portion of the looper thread between said finger and the eye of the looper in a predetermined position re-

gardless of the direction of feed and this 80 insures that the thread triangle, consisting of the looper thread, the looper, and the needle thread loop, shall be properly positioned and held open for the needle to enter.

It is understood of course, that if this 85 positioning finger is not used when the fabric is fed forward toward the operator, the point where the looper thread is at-

tached to the fabric moves in the same direc- 90 tion as the lateral movement of the looper, and it will be impossible for the needle to get into the needle thread loop or thread triangle if this positioning finger is not used.

The reversible feed may be of any desired 95 character, but it preferably consists of a treadle controlled mechanism which may be shifted when the treadle is depressed so as to cause the feed toward the operator, and when said treadle is released, a spring shifts the parts so as to cause the feed to be in a normal direction, that is, away from the 100 operator.

Referring more in detail to the drawings, I have shown my improvements as embodied in a sewing machine which includes a supporting bed 1 provided with the usual 105 bearings 2, 2 on which is mounted a work support 3 having a thread plate 4. The machine is provided with the usual over-

hanging arm 5 which carries a needle head 6 in which the needle bar 7 reciprocates. Said needle bar is reciprocated by the usual needle lever 8. Mounted in said needle bar 9 is a needle 9. This needle is of the thread carrying type. Cooperating with the needle beneath the work support is a thread carrying looper 11. Said looper is mounted on a looper carrier 12 which in turn is pivoted at 13 to a rocking looper support 14. The looper carrier is oscillated on its support by means of a link 15. The support is oscillated in the usual way from the main shaft 16 located beneath the work support. 15 This thread carrying looper moves forward into the needle thread loop and is then moved laterally for its needle avoiding movement and thus cooperates with the needle in making the well known two thread lock chain stitch. 20 The material is fed across the work support by means of a feed dog 17. The feed dog 17 is carried by the shank 18 which is mounted in the feed bar 19. The feed bar 25 19 is fixed at its rear end to a pin 20 which is pivotally supported in the feed rocker 21. The feed rocker 21 is in turn pivoted so as to swing about the center 22 as an axis. The feed bar is raised and lowered by means 30 of an eccentric 23 shown in dotted lines in Fig. 4. This eccentric is carried by the main shaft 16. As the main shaft rotates, the feed bar 19 will be raised and lowered carrying the feed dog into and out of engagement with the fabric. The feed rocker is oscillated for moving the feed dog back and forth by means of a crank 24 which is adjustably carried by crank disk 25 on the forward end of the shaft 16. A short 40 stub shaft 26 is mounted in a bracket 27 secured to the bed 1 by suitable screws 28. Fixed to this stub shaft is a rocker arm 29. Said rocker arm 29 is pivoted at 30 to a link 31 which in turn is connected to the crank 24 so that as the crank rotates, this rocker arm 29 will be oscillated. Said rocker arm 29 is formed with a projecting slotted plate 32. The slot is indicated at 33. An arm 34 is 45 fixed to the shaft 35 and this shaft 35 carries the rock frame for the feed bar. This arm 34 is connected by means of a link 36 to the slotted plate 32. Said arm is forked at its upper end and a pin 37 passing through the forked ends of the arm rides in the slot 33. It will be noted that the slot 33 extends equally to the right and left of the center 38 which is the axis of the stub shaft 26 carrying the rocker arm 29. When 50 the link 36 is positioned as shown in Fig. 2 with the upper end of said link at the extreme right of the slot 33, the feed is in a normal direction as indicated by the arrow in said figure. When, however, this link is shifted to the other end of the slot, as shown in Fig. 3, then the direction of feed is in the

opposite direction as indicated by the arrow in said figure. It will readily be seen that when the link 36 is shifted from one end of the slot to the other, that the endwise movements imparted to the link are reversed 70 in timing with the other parts of the machine, for the reason that the upper end of the link passes from one side of the pivotal center 38 to the other. An adjustable stop 39 is provided for limiting the movement of the link 36 to the left, and by adjusting this stop, the length of feed when reversed, may be made of the same length or a different length from that when the feed is normal.

As a means for shifting the link 36, I have provided a treadle controlled rock lever 40 which is mounted to turn freely on the shaft 35, and is connected by means of a flexible chain or the like, indicated by the broken line 41, to a suitable treadle or knee shift. This rock lever has an upwardly extending arm 42 and a link 43 connected to said arm 42, and the link 43 serves as a means for shifting said link 36 when said rock lever 40 is oscillated. A spring 44 90 bearing against an arm 45 formed as a part of the rock lever 40, normally turns the rock lever so as to hold the parts in the position shown in Fig. 2, and this is the position when the feed is normal. When the treadle is depressed, then the parts are shifted to the position shown in Fig. 3 and the feed is reversed.

After the looper has moved forward into the needle thread loop, it is then moved 100 laterally to the other side of the needle. As the looper moves laterally, the feed takes place, and the normal feed is in a direction opposed to the lateral movement of the looper. The thread running from the thread eye to the previous stitch in the fabric, will be carried by the feed away from the looper, when the feed is normal. With the looper moving at right angles to the line of feed as described above, and the feed operating 110 in a normal direction, that is, away from the operator, the thread triangle consisting of the looper thread, body of the looper, and the needle thread loop, will be properly positioned for the needle to enter, and thus the needle enters the needle thread loop and the proper stitch is formed. When, however, the feed is reversed, then the fabric moves toward the operator, and the point of attachment of the looper thread to the fabric 115 where the previous stitch was formed, is now moved toward the operator, and in the same direction as the lateral movement of the looper, and unless some means is provided to hold open the thread triangle, or 120 looper thread loop, the needle will skip the same. I have provided such a means which consists of a thread positioning finger 46. Said thread positioning finger 46 is provided with a thread engaging hook end 47 and 130

a shank 48 which is adapted to extend into a sleeve 49 mounted on the upper end of the carrier 50 which supports and operates said positioning finger. The shank is secured in the sleeve by means of a set screw 51. The carrier 50 is mounted on the upper end of a support 52. Said support is provided with a rib 53 which engages a recess in the carrier, and a screw 54 serves as a means for securing the parts together. The support 52 is fixed to a pivot pin 55 and this pivot pin 55 is mounted to oscillate freely in bearings 56, 56 carried by a bracket 57. The bracket 57 is secured by bolts 58 to the bed 10. 1. The support 52 is oscillated on its pivotal support by means of a cam 59 mounted on the main shaft 16. Extending through the support 52 is a short shaft 60. Secured to the end of said short shaft 60 are two arms 61 and 62. These arms engage opposite sides of the cam 59. The arms are secured to the shaft 60 by means of a clamping screw 63. This clamping screw rigidly secures the arms to the shaft 60 but permits 20 the shaft 60 to freely oscillate in the support 52.

The pivotal axis of the support 52 is in a line which cuts the vertical plane containing the feed at an acute angle. The looper cuts said vertical plane containing the feed at right angles as it moves into the needle thread loop. As a result, this support 52 will move so as to carry the thread positioning finger across the path of movement of the looper, and thus causes the hook 47 to engage the looper thread. 35

In Fig. 9 of the drawings, the material being stitched is indicated at F, the needle thread at n, and the looper thread at l. 40 It will be noted that the looper thread between the fabric and the eye of the looper is engaged by the hook of the positioning finger. In this figure, the needle thread loop is around the looper, and this looper positioning finger will hold the looper thread always in a predetermined position regardless of the direction of feed so as to insure that the thread triangle or looper thread loop will be properly positioned for 45 the entrance of the needle. In Fig. 10, I have shown diagrammatically the position of the parts with the feed in normal direction and at the time that the needle is about to enter the thread triangle or looper thread loop. The looper 11 has moved laterally for 50 its needle avoiding movement. The previous stitch point is indicated at s. The threads are carried away from the looper by the feed which is in the direction of the arrow shown in this figure. The looper thread positioning finger 46 is shown as in engagement with the looper thread although 55 when the feed is in a normal direction, this positioning finger could be dispensed with. Its presence, however, does make more cer-

tain the opening of the looper thread loop for the needle to get down into the triangle which is clearly shown in this Fig. 10. In Fig. 11, the feed is reversed as indicated by the arrow and the fabric is moved toward the operator, carrying the concatenations of the threads at the previous stitch formation to the position shown at s'. The positioning finger 46 now becomes the active factor in the spreading of the triangle or looper thread loop. The thread of the looper runs from the eye of the looper rearwardly to this positioning finger and thence forwardly to the previous stitch. The needle as it comes down will pass between the strand of the looper thread, running from the eye of the looper to the positioning finger 46 and the body of the looper, and thus will enter the thread triangle or the looper thread loop. 70 75 80 85

In Fig. 12, I have shown in full lines the looper as it is approaching the forward end of its stroke. In dotted lines, the looper is moved laterally to avoid the loop. The thread positioning finger 46 moves from 90 the full line position to the dotted line position, and as it moves in this path diagonally across the path of the looper, the looper thread will be engaged by the hook 47 of said positioning finger. 95

It will be obvious that other forms of reversible feeds may be used from that herein shown and described specifically. The particular invention here is directed to the combination of a reversible feed and a stitch forming mechanism and the associated device which insures the formation of stitches when the feed is reversed. 100

It is obvious also that changes in the form of the associated device which insures the form of the stitch with the feed reversed may be changed without departing from the spirit of the invention which is set forth in the appended claims. 105

Having thus described the invention, what I claim as new and desire to secure by Letters-Patent, is—

1. The combination with feeding mechanism including devices whereby the direction of feed may be reversed; of stitching mechanism including a thread carrying needle, and a thread carrying looper cooperating therewith, and means for engaging the looper thread between the looper eye and the previous stitch for holding the looper thread so as to insure the needle entering the looper thread loop when the feed is reversed. 115 120

2. The combination with feeding mechanism including devices whereby the direction of feed may be reversed; of stitching mechanism including a thread carrying needle, and a thread carrying looper cooperating therewith, a looper thread positioning finger, and means for supporting and mov- 125 130

ing the same whereby the looper thread between the eye of the looper and the previous stitch is engaged thereby and held so as to insure the needle passing into the 5 looper thread loop when the feed is reversed.

3. The combination with feeding mechanism including devices whereby the direction of feed may be reversed; of stitching 10 mechanism including a thread carrying needle, and a thread carrying looper co-operating therewith, a looper thread positioning finger having a hooked end, and means for operating said finger so as to cause said 15 hooked end to engage the looper thread between the eye of the looper and the previous stitch and position said thread so as to insure that the needle will enter the looper thread loop when the feed is reversed.

20 4. The combination with feeding mechanism including devices whereby the direction of feed may be reversed; of stitching mechanism including a thread carrying needle, and a thread carrying looper co-operating therewith, a looper thread positioning finger having a hooked end, means for oscillating said finger in a path crossing the plane of movement of the looper whereby 25 said finger is caused to engage the looper thread between the eye of the looper and the previous stitch for positioning said thread so as to insure that the needle will pass into the looper thread loop when the feed is reversed.

35 5. The combination with feeding mechanism including devices whereby the direction of feed may be reversed; of stitch forming mechanism including a thread carrying needle, a thread carrying looper moving back and forth in a plane at right angles to the line of feed and laterally for a needle avoiding movement, and a looper thread 40 positioning finger movable into engagement with the looper thread between the eye of the looper and the previous stitch for positioning said thread so as to insure that the needle will enter the looper thread loop when the feed is reversed.

45 6. The combination with feeding mechanism including devices whereby the direction of feed may be reversed; of stitch forming mechanism including a thread carrying needle, a thread carrying looper moving back and forth in a plane at right angles to the line of feed and laterally for a needle avoiding movement, a looper thread positioning finger having a hooked end, and means for moving said finger in a direction 50 diagonally across the plane of movement of the looper as it enters the needle thread loop

whereby said hooked end engages the looper thread between the eye of the looper and the previous stitch for positioning the same for the entrance of the needle when the 55 feed is reversed.

7. The combination with feeding mechanism including devices whereby the direction of feed may be reversed; of stitch forming mechanism including a thread carrying needle, a thread carrying looper moving back and forth in a plane at right angles to the line of feed and laterally for a needle avoiding movement, a looper thread positioning finger, a carrier for said finger, a support for said carrier, said support being pivoted so that the finger moves back and forth in a single plane diagonally of the plane of movement of the looper as the looper moves into and out of the needle 70 thread loop, whereby said thread finger engages the looper thread and positions the same so as to insure the needle entering the looper thread loop when the feed is reversed.

8. The combination of a thread carrying looper; of a looper thread positioning finger cooperating therewith, a support for said finger, means for oscillating said support in a plane diagonally of the path of movement 80 of the looper as the looper moves into and out of the needle thread loop for causing said finger to engage the looper thread.

9. The combination with a thread carrying looper; of a looper thread positioning finger, a support for said finger, means for pivoting said support whereby the same swings about an axis inclined to the plane of movement of the looper as it enters the needle thread loop, said looper thread positioning finger having a hooked end for engaging the looper thread between the eye of the looper and the previous stitch.

10. The combination of a thread carrying looper, a main shaft, means for oscillating said looper back and forth in a direction parallel with the shaft, and for moving said looper laterally to avoid the needle, a looper thread positioning finger, a support for said finger pivoted to swing in a plane at an acute angle to the plane of movement of the looper as it enters the needle thread loop, a cam on said main shaft, spaced arms co-operating with said cam, said arms being pivotally connected to said support so as to swing in a plane parallel to the longitudinal axis of the shaft.

In testimony whereof, I affix my signature.

JAMES R. MOFFATT.
